UNITED STATES PATENT OFFICE.

JESSE K. THISSELL, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE AND METHOD OF MAKING SHOES.

1,302,994.

Specification of Letters Patent. Patented May 6, 1919.

Application filed December 28, 1915. Serial No. 62,618.

To all whom it may concern:

Be it known that I, JESSE K. THISSELL, a citizen of the United States, residing at Lynn, in the county of Essex and State of Massachusetts, have invented certain Improvements in Shoes and Methods of Making Shoes, of which the following description, in connection with the accompanying drawings, is a specification, like reference characters on the drawings indicating like parts in the several figures.

The present invention relates to improvements in the manufacture of shoes and more especially it concerns the manufacture of shoes of the type commonly termed turn shoes in the manufacture of which the shoe uppers are secured to the soles while they are inside out, the shoes being thereafter turned right side out.

It is a common and universal practice in the manufacture of turn shoes to provide shoe upper stiffening elements such as counter elements or heel stiffeners or toe boxes to assist in maintaining the shape desired and support for the shoe, these stiffening elements being interposed between the layers of the upper materials as between the upper and the lining.

An object of the present invention is to improve the manufacture of turn shoes by providing for separately incorporating previously shaped shoe upper stiffening elements in the shoes to the end that turn shoes may be produced more economically and efficiently at the same time improving the fit and appearance of the shoe.

The present invention is herein set forth by way of illustration with particular reference to the incorporation of previously molded counters or heel stiffeners, although it is to be recognized that the invention is not limited thereto.

In the manufacture of turn shoes as now made, it is the usual practice to employ a substantially flat unmolded leather counter or heel stiffener for the shoe. The method ordinarily followed in incorporating this kind of a counter in the shoe consists in thereafter arranging the counter between the shoe upper and lining, assembling the upper inside out upon the last, and attaching the upper, counter and lining to the shoe sole, the counter, prior to its incorporation in the shoe, being rendered pliable by

tempering it with moisture. Then, after the first last is withdrawn and the shoe turned right side out and relasted, the counter is conformed to the contour of the heel portion of the last, the shoe remaining on the second last until the counter has dried to the shape imparted to it.

Such leather counters or heel stiffeners are expensive and considerable time and labor are involved in conforming the shoe upper and the counter to the desired shape about the heel end of the last and in allowing the shoe to remain on the second last a sufficient length of time to enable it to dry into shape. The use of previously molded counters in the manufacture of turn shoes is, however, recognized as being very desirable because of their permanently inflexible character and effectiveness as shape producing and retaining elements and because of their economy, molded counters being commonly made from fiber stock which is relatively inexpensive and at the same time very efficient. The peculiar conditions attendant upon the manufacture of turn shoes by the methods heretofore in use have, prior to my invention, prevented previously molded counters from being satisfactorily incorporated in turn shoes.

In one of its aspects the present invention contemplates a novel method of incorporating a previously shaped upper stiffening element in a turn shoe which consists in assembling a shoe upper having a lining inside out upon a last, together with a sole, lasting the shoe and attaching the upper and lining to the sole and leaving the lining unattached to the sole around an end portion of the shoe, incorporating a molded upper stiffening element in the said end portion of the shoe prior to the completion of the operation of turning the shoe right side out, completing the turning of the shoe right side out and disposing the said upper stiffening element between the shoe upper and the lining and thereafter relasting the shoe and performing subsequent operations to complete its manufacture. In practice the molded counter is preferably first located on the sole in the final position it is to occupy in the completed shoe in which position it is attached to an underlying part of the shoe before the shoe is turned right side out. To provide for disposing the counter between

the upper and the lining after the shoe upper is reversed, the lining is left unattached to the sole around the heel portion a distance approximating the length of the counter wings and in order further to facilitate this arrangement of the counter, the lining is preferably slit at points on opposite sides of the shoe where the attachment of the lining to the sole terminates.

10 In another of its aspects, the invention contemplates anchoring the forward extremities of the counter which project forwardly of the heel breast line of the shoe to the sole by means which do not appear on the finished sole of the shoe so as not to detract from the neat appearance of the shoe. In the illustrated application of the invention this is accomplished by providing the counter with a bottom piece or tuck to which the forward extremities of the counter are connected and by attaching the counter to the sole with fastenings which pass through the said bottom piece and an underlying portion of the sole within the area of the heel seat. This bottom piece for the counter, in addition to facilitating the attachment of the counter in proper position on the sole, serves to connect the forward extremities of the counter together and to the sole so that they are prevented from spreading and the counter will not become distorted in the shoe.

The invention further comprehends novel step products at different stages in the manufacture of turn shoes before their completion whether or not the process herein set forth is practised in its entirety. One of such step products comprises a shoe upper wrong side out, a sole to which the upper is connected and a molded counter attached in upright position on the heel seat portion of the sole.

45 A step product provided by the invention at another stage in the manufacture of a turn shoe comprises a shoe upper inside out, a sole to which the upper is secured, a previously molded counter arranged on the heel end of the sole in the relative position it is to occupy in the finished shoe, a bottom piece 50 to which the forward ends of the counter are connected, and fastenings attaching the counter through the said bottom piece to the sole.

These and other aspects and features of the herein described method, as well as the novel shoe products provided by the invention, will be apparent from the following description when considered in connection with the accompanying drawings, and the novel features will then be pointed out in the appended claims.

In the drawings,—

Figure 1 is a perspective view of a preferred form of the counter used in practising the method of the present invention;

Fig. 2 is a perspective view showing the counter applied to the shoe before the shoe is turned;

Fig. 3 is a view partly in section showing the forepart of the shoe upper turned right 70 side out and the heel portion of the upper in the process of turning; and

Fig. 4 is a side elevation showing the finished shoe.

In carrying out the method of the present invention in one manner in which it has been successfully practised, the shoe upper comprising an upper 2 and a lining 4 together with the box toe is first assembled upon the last 6 inside out or with the lining 20 outside and the sole 8 having the usual shoulder and sewing channel upon its upper surface is also temporarily secured to the last bottom. The assembled upper is first sewed to the sole 8 completely around the sole by a continuous seam 10, the lining however is only secured by the seam 10 about the forepart and along either side of the shank, the heel portion of the lining being left unsecured to the sole as shown in Fig. 2. A counter 12 preferably of leatherboard or like material and having the shape imparted to it which is desired in the finished shoe is now permanently attached to the inlay or flesh side of the heel end of the sole 8 in its final position in the shoe by fastenings 14. Preferably the counter 12 is attached to the sole 8 before the first last is removed from the shoe, since it enables the operator to position the counter on the sole more conveniently and with greater accuracy and also allows the fastenings 14 to be clenched upon the metal heel plate ordinarily provided on the heel end of the last. In the illustrated preferred form of the invention the counter 12 is provided with a bottom or heel seat piece 16 shaped to fit inside of the counter and overlie the inturned flange 18 to which the bottom piece is secured by any convenient form of fastening. This heel seat piece 16 serves both to maintain the molded condition of the counter and prevent it from spreading out during wear of the shoe and also to provide a smooth heel seat for the shoe.

115 A further important function served by the heel seat piece 16 is to form a connection for the forward extremities of the counter projecting beyond the heel breast line of the shoe. Considerable strain is placed upon these counters both during the manufacture of the shoe and the subsequent wear of the shoe and unless they are positively secured against spreading the counter is liable to be easily distorted so that the heel portion of the shoe does not present the desired appearance and the counter does not provide the proper support in the shoe for which it is intended. It will be seen that by connecting the forward extremities of the counter 125

to the heel seat piece as shown in Fig. 1, the forward extremities of the counter are in themselves connected together against spreading and indirectly they are connected 5 to the sole by reason of the heel seat member to which they are connected being tacked to the sole within the area of the heel seat.

It will be observed that although as herein set forth the present invention provides 10 for incorporating a counter in the shoe construction before the shoe is turned right side out regardless of whether in the manufacture of the shoe the method herein exemplified is practised in its entirety, the invention provides as a novel product at one stage in the manufacture of a turn shoe, a shoe construction comprising a shoe upper wrong side out, a sole to which the upper is connected, and a previously molded counter 15 attached in upright position to the heel end of a sole as illustrated in Fig. 2. As illustrated in Fig. 4, the invention further provides a step product at another stage in the manufacture of a turn shoe which comprises 20 a shoe upper inside out, a sole to which the upper is connected, a previously molded counter located on the heel end of the sole in the relative position it is to occupy in the finished shoe, a heel seat member to which 25 the forward ends or wings of the counter are secured, and fastenings attaching the counter through the said heel seat member to the sole. It is to be understood, however, that the step products herein defined may or may 30 not be obtained by following in detail and in order all the steps herein described. Subsequently to the incorporation of the molded counter in the shoe construction the operations performed comprise, in accordance 35 with the process of the invention, withdrawing the first last 6 and then turning the shoe so as to bring the upper right side out with the upstanding counter disposed between the shoe upper and the lining. According to the 40 general practice the forepart of the shoe is first turned, as shown in Fig. 3, and then the heel portion of the shoe is turned. In turning the heel portion of the shoe the lining 4 which is not secured to the sole 8 at its 45 heel end is first pulled upwardly over the counter 12 in the manner indicated in Fig. 3 which also turns the upper 2 upwardly over the counter. After the upper 2 has been turned right side out about the counter the lining 4 is turned in over the inner face of 50 the counter thus disposing the counter between the upper and the lining. The inner face of the counter is preferably coated with cement so as to prevent the lining from 55 wrinkling and the lower marginal edge of the lining is turned out onto the heel seat piece and secured preferably by cement. The subsequent operations on the shoe to 60 complete its manufacture follow those now generally practised and include inserting a

“second” last in the shoe, together with a shank stiffener member which will overlie the inturned margin of the lining on the heel seat piece and the attachment of a heel 70 to the shoe. It will be noted that the turning of the shoe upper right side out does not distort or strain the counter 12 from the shape originally imparted to it so that when the shoe is relasted the counter conforms to the heel end of the last and no further 75 conforming and shaping operations are necessary. Furthermore it will be seen that the method of making turned shoes above described does not involve any material departure from the methods heretofore employed in manufacturing turn shoes and a better fitting and more shapely shoe is produced.

It is to be understood that while the invention is herein illustrated in its application to the incorporation of a molded counter in a turn shoe, the invention is not intended to be limited thereby but is of general utility in the manufacture of turn shoes 85 wherein it is desired to incorporate a shoe upper stiffening element in the shoe upper.

Having described my invention, I claim as new and desire to secure by Letters Patent of the United States:—

1. That improvement in the art of making turned shoes which consists in attaching an upper inside out to a sole, attaching a counter which is molded to the final shape desired in the finished shoe to an underlying part of the sole, turning the shoe right side out, and then finishing the shoe in the usual manner.

2. That improvement in the art of making turned shoes which consists in attaching an assembled upper inside out to a sole, positioning a molded counter on the shoe and attaching it to the sole, turning the shoe right side out and arranging the upper outside the counter and the lining inside the counter, and then finishing the shoe in the usual manner.

3. That improvement in the art of making turned shoes which consists in attaching an upper and lining inside out to a sole, providing a counter which is molded to the final shape desired in the finished shoe, permanently attaching the counter to the heel end of the sole in the relative position it is to occupy in the shoe, then turning the shoe right side out and arranging the upper outside the counter and the lining inside the counter, and thereafter finishing the shoe in the usual manner.

4. That improvement in the art of making turned shoes which consists in attaching an upper and lining inside out to a sole, leaving said lining unattached to the sole at its heel end, tacking a molded counter in upright position on the heel portion of the sole, turning the shoe right side out and 130

disposing the counter between the upper and the lining, and then finishing the shoe in the usual manner.

5. That improvement in the art of making turned shoes which consists in attaching a lined upper inside out to the sole completely around the sole but leaving the lining unattached at the heel portion, providing a previously molded counter having an 10 inwardly extending flange and a bottom piece connecting the forward ends of the flange, locating the counter in the relative position it is to occupy in the finished shoe, attaching the counter by fastenings inserted 15 through the bottom piece into the heel end of the sole, turning the shoe right side out in such manner as to interpose the counter between the lining and the upper, and then finishing the shoe in the usual manner.
- 20 6. That improvement in the art of making shoes which consists in assembling a sole with an upper and lining inside out on a last, securing the upper to the sole completely around said sole and securing the 25 lining to the sole throughout the forepart and shank, attaching a permanently inflexible counter to the heel end of the sole in the relative position it is to occupy in the finished shoe, turning the shoe right side out 30 and interposing said counter between the lining and the upper, relasting the shoe and performing subsequent operations in the usual manner.

7. That improvement in the art of making shoes which consists in assembling a 35 sole with an upper and lining inside out on a last, securing the upper to the sole completely around said sole and securing the lining to the sole throughout the forepart 40 and shank of the sole, providing a previously molded counter having a bottom piece, permanently attaching said counter to the heel end of the sole in the relative position it is to occupy in the finished shoe by 45 fastenings inserted through said bottom piece and into the sole, withdrawing the last, turning the forepart of the shoe right side out, then drawing the upper and lining over the counter so as to interpose the counter 50 between the lining and upper, relasting the shoe and subsequently securing the free marginal portion of the lining to the upper surface of the bottom piece of the counter.

8. That improvement in the art of making turn shoes which consists in assembling a 55 shoe upper with its lining outside upon a last, together with a sole, lasting the shoe and attaching the upper and lining to the sole but leaving the lining unattached to the 60 sole around an end portion of the shoe, incorporating a molded upper stiffening element in the said end portion of the shoe prior to the completion of the operation of 65 turning the shoe right side out, completing the turning of the shoe right side out and

disposing the said upper stiffening element between the shoe upper and the lining, and thereafter relasting the shoe and performing subsequent operations in the usual manner.

9. That improvement in the art of making turn shoes which consists in attaching a shoe upper with its lining inside out to a sole but leaving the lining unattached to the sole around the heel end of the shoe, incorporating a molded counter in its final relative position in the shoe prior to the completion of the operation of turning the shoe right side out, and completing the turning of the shoe right side out and disposing the 75 counter between the upper and the lining, and thereafter performing subsequent operations upon the shoe in the usual manner.

10. That improvement in the art of making turn shoes which consists in attaching a 80 shoe upper, including the lining, inside out to a sole but leaving the lining unattached to the sole around the heel end of the shoe, locating a molded counter on the heel end of the sole and fixing the position 85 of the forward ends of the counter in final relation to the sole, turning the shoe right side out and disposing the counter between the upper and the lining, and thereafter performing subsequent operations on the 90 shoe in the usual manner.

11. That improvement in the art of making turn shoes which consists in attaching a shoe upper, including the lining, inside out to a sole but leaving the lining unattached to the sole around the heel end of the shoe, locating a molded counter on the heel 100 end of the sole, attaching the counter to the sole in a manner to fix the position of the forward extremities of the counter, turning 105 the shoe right side out and disposing the counter between the upper and the lining, and thereafter performing subsequent operations on the shoe in the usual manner.

12. That improvement in the art of making turn shoes which consists in attaching the shoe upper, including the lining, inside out to a sole but leaving the lining unattached to the sole around the heel end of the shoe, locating a molded counter having 110 an inturned flange on the sole in the position it is to occupy in the completed shoe, attaching the counter to the sole to fix the position of the forward extremities of the counter, said attachment being made by securing the opposite flanges of the counter to a heel seat member and nailing the heel seat member to the sole within the heel seat area of the shoe, turning the shoe right side out and disposing the counter between the 115 upper and the lining, and thereafter performing subsequent operations on the shoe in the usual manner.

13. That improvement in the art of making turn shoes which consists in attaching a 120

shoe upper, including the lining, inside out to a sole around the heel end of the shoe, locating a molded counter on the sole in the position it is to occupy in the completed shoe 5 attaching the ends of the counter which project forwardly of the heel breast line to the sole by means so arranged as not to appear on the exterior finished surface of the shoe, turning the shoe right side out and 10 disposing the counter between the shoe upper and the lining, and thereafter performing the subsequent operations upon the shoe in the usual manner.

14. A step product in the manufacture of 15 turn shoes which comprises a shoe upper inside out, a sole, the upper and sole being secured together, and a molded counter attached to the sole in the relative position it is to occupy in the completed shoe.

16. A step product in the manufacture of 20 turn shoes comprising an upper wrong side out, a sole, the upper and the sole being secured together, a molded counter located in upright position on the heel end of the sole, a heel seat member to which the forward 25 ends of the counter are secure, and fastenings for attaching the counter to the sole.

16. A step product in the manufacture of 20 turn shoes comprising an upper wrong side out, a sole, the upper and the sole being secured together, a molded counter seated in upright position on the heel end of the sole, a heel seat member attached to the counter and fastenings inserted through the said heel seat member and into the sole to attach the counter to the sole.

In testimony whereof I have signed my name to this specification.

JESSE K. THISSELL.
